UNITED STATES PATENT OFFICE

172,531

GAME APPARATUS

Harold R. Bennett, Newton, Kans.

Application May 20, 1953, Serial No. 25,115

Term of patent 14 years

(Cl. D34—5)

To all whom it may concern:

Be it known that I, Harold R. Bennett, a citizen of the United States of America, residing at Newton, in the county of Harvey and State of Kansas, have invented a new, original, and ornamental Design for a Game Apparatus, of which the following is a specification, reference being had to the accompanying drawing, forming a part thereof.

Fig. 1 is a top plan view of the game apparatus, showing my design,

Fig. 2 is a side elevational view thereof,

Fig. 3 is an end elevational view thereof,

Fig. 4 is a sectional view taken on line IV—IV of Fig. 1, and

Fig. 5 is a fragmentary sectional view taken on line V—V of Fig. 1.

The drawing is lined to represent contrasting colors. Portions of the drawing figures are lined to

indicate transparency, and a portion of Fig. 1 is broken away to show the cubical gamepieces inside of the transparent drum.

I claim:

The ornamental design for a game apparatus, as shown and described.
